CONCRETE FORM STRUCTURE

Donald A. Nyman, 3800 S. Jason St., Englewood, Colo.
Filed Apr. 3, 1961, Ser. No. 100,125
6 Claims. (Cl. 25—131)

This invention relates to an improved arrangement of the knock-down type designed for use in concrete form structure for construction of a poured concrete wall. Essentially the invention includes locking device means cooperable with a special tie wire and the inner and outer wall sections which permits speedy and secure erection of concrete forms and at the same time provides extreme flexibility, speed and ease in stripping.

As is well known, many concrete forms now in existence are made up of a plurality of vertical form sections of substantially rectangular shape and pairs thereof that provide the inner and outer walls are disposed in coplanar relation with the edges in abutment and adapted to be secured together detachably to define joints between the abutting sections. A locking device is utilized to so detachably connect pairs of said sections or panels are maintained in spaced coplanar relationship by means of tie wires that cooperate with the locking device of each pair, thus providing inner and outer walls of the form. This general type of construction of concrete forms probably can be classified as being of the "knockdown" type and is exemplified by U.S. Patents 2,825,956 and 2,898,659. Such prior art techniques have proved generally satisfactory but the setting up and taking down or "stripping" of such construction is somewhat cumbersome and time consuming and of course this increases the cost of the end product, such as a concrete foundation.

It is a primary object of this invention to provide an improved concrete form construction of the knock-down type which greatly simplifies the erection and stripping of concrete forms, thus reducing the cost substantially.

It is also an object to provide for such erection and stripping of concrete forms by means that greatly reduces the time requirements, all without sacrificing the necessary results of a secure form.

Another object is to provide in a concrete form construction of the type mentioned an improved locking device for cooperation with a special tie wire whereby the inner and outer walls of the form are firmly braced in parallel spaced relation and the pairs of coplanar panel sections are securely but detachably connected.

Still another object of the invention is to provide a form construction made up of a plurality of locking devices and tie wires cooperating therewith and the panel sections which are simple to manufacture and operate and yet which provide the necessary strength to withstand extreme conditions.

Other objects and advantages of the invention will become apparent by referring to the accompanying drawing wherein the preferred embodiment is illustrated and wherein:

FIGURE 1 is a perspective view of a portion of a concrete form structure made in accordance with the invention;

FIGURE 2 is a rear elevation view of the locking structure exemplified in FIGURE 1;

2

FIGURE 3 is a sectional view taken along the line 3—3 of FIGURE 2;

FIGURE 4 is a view similar to that of FIGURE 3 showing the parts following actuation of the locking device;

FIGURE 5 is a sectional view taken along the lines 5—5 of FIGURE 4; and

FIGURE 6 is a perspective view of the tie wire utilized with this invention.

Referring to the drawing, the numerals 1 and 2 represent the outer and inner walls, respectively, of a concrete form structure made in accordance with this invention, the walls being positioned and maintained by means to be described in parallel spaced relation. Each of these walls, in accordance with standard practice, is made up of a plurality of sections, the height and width of each wall including enough sections to approximate, for example, the depth of a basement wall which is to be made from poured concrete. The sections or panels are disposed on each side of the form, a distance representing the basement wall width, in edge to edge abutting relationship and they are adapted to be secured together detachably in coplanar relationship to define joints between the the abutting sections. The spaced and coplanar relationship is accomplished by means of a plurality of tie wires T and locking devices L which cooperate with the tie wires and the edges of each section S in making this securing. Each panel or section S is preferably of plastic construction for lightness and cheapness and includes, although this is by no means to be construed as limiting, a panel portion 6 having a reinforcing frame consisting of side edge members 7 and 8, top cross pieces 9 and a bottom cross piece together with intermediate cross pieces or braces (not shown), all forming an integral part of a section S in accordance with known forming techniques, the interiorly positioned face of each section against which the concrete is poured being substantially flat. The side edge members 7 and 8 are more clearly shown in FIGURES 2 and 3 in their positioned abutting relationship to define joints therebetween with the side edge 8 on each form section S disposed in side to side abutment with the side edge 7 of the next adjacent form section. Thus the vertical joints defined by the side edge members 7 and 8 and for that matter all portions of each section are in abutting coplanar relationship. Each side edge member 8 is notched out or milled vertically as at 11 to provide a space to accommodate the end portion of the tie wire T and although not necessary, as shown, each edge member 7 is similarly notched at 10 to provide from the mating or registered notches a combined opening 12 considerably greater than the height of the preferred tie wire T so there will be no problem in assembling the form construction of registering the tie wire in the combined opening 12.

Now as to the important aspects of this invention, it is clear from referring to FIGURES 1 and 2 that the form construction is assembled and maintained in its desired position by a plurality of tie wires T and locking devices L and since the operation and structure of each locking device and tie wire is identical, only one will be described, there being two locking devices that cooperate with each tie wire to maintain the walls in proper spaced relation and the sections in proper coplanar relation. First of all, each tie wire T consists of an elong-

gated body of a length to extend between and beyond the panels by passing through openings 12 and, as shown in FIGURE 6, at each end portion 15 there is provided adjacent the extremities thereof a pair of vertically aligned oppositely directed grooves 16 and 17. Struck out from each tie wire are projecting aligning prongs 18, the purpose of which will be described hereinafter.

Each locking device L has a body portion 20 of substantial thickness and of substantial semi-circular shape. Viewing at FIGURES 3 and 4, the vertical side walls are substantially parallel with wall 21 forming the exterior wall and with a portion of the interior wall being adapted to flushly engage a side edge 8. To securely but detachably engage each locking device L to edge 8, body portion 20 is counterbored at 22 and 23 at its upper and lower extremities respectively thereof as well as recessed as at 24 to receive bolt means 25 extending from edge member 8 and thus by standard means body portion 20 is attached to edge 8, it being noted that the head of means 25 is flush with cut-out area 11 so as not to interfere with the space provided by opening 12. At the approximate vertical center thereof, wall 21 is indented in the form of a substantial V, the walls of the V being shown at 26 and 27 and the apex of the V preferably extending the depth of body portion 20. Spaced at predetermined distances on each side of the V apex are pins 29 and 30 which are integral with portion 20 and extend therefrom a substantial distance. As shown in FIGURE 3, this distance is at least sufficient to pass beyond the opening 12 and it will be noted that the pins 29 and 30 are mounted on body portion so that they may be positioned outward of the edges 7 and 8 and further they are of a diameter approximating grooves 16 and 17 of the tie wire so they may be received therein at least in part.

At its center, portion 20 has an opening therethrough at 32 whereby means in the form of a locking member 35 may loosely extend therethrough, although it is prevented from being removed from the body portion 20 due to its head 34 at one end which forms cam means and a hooked right angled portion 36 at its other end which forms gripping means. The head 34 has an inner face 28 that is V-shaped to substantially conform or match the V of face 21 and when the locking member 35 is located as in FIGURE 3, there is such matching and the gripping portion 36 is located at its most extreme distance from body portion 20. The body portion of the locking member is of a size to be received in one of the grooves 16 or 17. This completes the description of the parts of each locking device L, the critical portions thereof being the provision of any suitably shaped body 20, means to attach the latter so that at least one pin 29 or 30 may extend across an opening 12, the cam surface formed by walls 26 and 27, the locking means 35 having cam means 34 for cooperating with the cam surface and gripping means 36 that is exemplified as detoured or bent with respect to the main part of locking member 35 and which may be retracted into locking engagement with a section S.

In operation, the sections S are positioned as shown in FIGURE 1 after a desired number of locking devices are secured to each edge 8 in vertically spaced relation. The number of locking devices L on a given edge varies with the height of walls 1 and 2 but they each must be located on the edge 8 in the same vertical relation as on the edge of the next adjacent section and the pair of sections spaced directly opposite as should be apparent. Next a tie wire T is positioned to extend between the spaced sections with the end portions 15 passing beyond edges 7 and 8 and at this time the cam head 28 of each locking device that cooperates with the wire is located with its V flush with the V of edge 21 so that hooked portion 36 is spaced its maximum distance from an edge 8 and also out of the way of the sections to be joined, as illustrated by the locking devices shown at the left in FIGURE 1. The pin 29 and body 35 of each locking de-

vice passes through or has portions located in grooves 17 and 16, respectively. The panel sections to be joined are then positioned so edges 7 are coplanar with edges 8 and the struck out portions 18 insure this proper alignment as the panel sections to be joined are located so that their inner faces are flush with and resting against portions 18. At this time the heads of each locking device L are manually rotated with cam means 28 riding on the cam surface formed by the walls 26 and 27 and this results in the hooked portion or gripping means 36 being retracted into locking engagement with edges 7, as shown, and insuring that the abutting sections are tightly locked but yet readily detachable as should be apparent. The locking cooperation of the tie wires, both locking devices and the four edges should be clear.

The other pin 30 of each locking device L is utilized for what might be referred to as left hand operation when the locking devices are secured to edges 7 and portion 36 is to engage edge 8, and here again this operation in view of the foregoing should be clear. Although there must be cam action between the V of edge 21 and the head 34, it should be understood that the configuration of the cam and its engaged surface may be altered within the spirit of this invention to vary the amount of cam contact.

The foregoing disclosure and description in the invention is illustrative and explanatory thereof and various changes in the size, shape and materials, as well as in the details of the illustrated construction, may be made within the scope of the appended claims without departing from the spirit of the invention. The objects of this invention are believed to be apparent by reference to the detailed description.

What is claimed is:

1. In a concrete form structure for construction of a poured concrete wall including spaced parallel inner and outer walls, each made up of at least a pair of vertical sections disposed in coplanar relation with their side edges in abutment and adapted to be secured together detachably to define vertical joints between the abutting sections, the joints in the outer wall being in coplanar relation with the joints in the inner wall, and means for rigidly spacing said inner and outer walls comprising tie wires extending therebetween in right angled relationship thereto and protruding through the joints between abutting sections of both walls, the outer extremities of each wire having at least one groove therein, the combination therewith of a locking device for cooperation with each extremity of the wire for rigidly but detachably connecting the abutting sections, each locking device comprising a body portion secured to one of the side edges of the abutting sections, a pin extending from the body portion receivable in the tie wire groove, said body having a cam surface and a locking member supported by said body, the locking member having cam means cooperating with the surface and gripping means, said gripping means upon actuation of the cam means cooperating with the other side edge to bring the abutting sections into locked relationship and maintain said pin within the groove, the locking member being loosely carried by said body portion, the cam means being at one end thereof and the gripping means being at the other end thereof.
2. Structure as defined in claim 1 wherein the tie wire has at each extremity a pair of grooves oppositely directed and a portion of the locking member is received and maintained in the other groove.
3. Structure as defined in claim 2 wherein the body portion of the locking device has one wall having a portion thereof contoured to form the cam surface and the gripping means of the locking member comprises a hooked portion adapted to be retracted into locking engagement.
4. Structure as defined in claim 3 wherein the cam means is a head forming an integral part of the lock-

ing member, said head having a surface for manual cooperation with the cam surface.

5. Structure as defined in claim 1 wherein each tie wire includes aligning means to insure proper positioning of the sections prior to locking thereof.

6. Structure as defined in claim 1 wherein the locking member is located centrally of the body portion and the body portion of the locking devices includes a pair of pins equally spaced from the center of the body portion whereby the locking device may be secured to either of the side edges.
